Atty.

UNITED STATES PATENT OFFICE.

WALTER W. LAFLAME, OF PITTSBURGH, PENNSYLVANIA.

YIELDABLE COUPLING.

1,275,568.

Specification of Letters Patent. Patented Aug. 13, 1918.

Application filed June 12, 1917. Serial No. 174,252.

To all whom it may concern:

Be it known that I, WALTER W. LAFLAME, a citizen of the United States, residing at Pittsburgh, in the county of Allegheny and

5 State of Pennsylvania, have invented new and useful Improvements in Yieldable Couplings, of which the following is a specification.

This invention relates broadly to expandable couplings or connections for various articles such as belts, garters, suspenders, check reins and the like that require, or are better fitted for their operative functions, when provided with a resilient member 15 somewhere in their length, that will permit expansion and contraction under unusual tension or relaxation. The invention therefore has for its object to provide a simple, strong and readily operable coupling or connection for the purpose set forth, which being spring controlled, will yield under tension and when released therefrom will contract and return to normal size.

A further object of the invention is to 25 provide a resiliently expandible coupling or connection, which for convenience of description will be hereinafter called an expansive buckle, or simply a buckle, which being made of few parts and principally of 30 sheet metal cut and stamped to shape, may be manufactured at relatively small cost, and thus enable the device to be placed on the market at a reasonable price.

With the above as the principal objects 35 in view, the invention consists of the novel construction, combination and arrangement of parts, hereinafter described, pointed out in the appended claims and illustrated in the accompanying drawings, in which

40 Figure 1 is a front view of the improved coupling or expansion buckle;

Fig. 2 is a top view of the same;

Fig. 3 is an elevation of the interior structure of the buckle, one side of the casing 45 being removed;

Fig. 4 is a vertical sectional view on line 4-4 of Fig. 1;

Fig. 5 is a view in elevation showing the buckle in expanded position and provided 50 with a modified form of connecting links;

Fig. 6 is a face view of the view used as a yielding coupling for suspenders with modified connecting links;

Fig. 7 is an edge view of the device of 55 Fig. 6;

Figs. 8 and 9 are detail views of one of the connecting links of the preferred form, and

Figs. 10 and 11 are detail views of a modified connecting link.

In the drawing, 15 indicates a casing that 60 forms the body of the expansion buckle and is made of two plates 16 and 17 of equal size, circular or of any other desired shape, with their edges bent to form narrow flanges 18 and 19 perpendicular to the plates. 65 When assembled, the edges of the flanges bear upon and rotate against each other, being connected by a pintle 20, riveted or otherwise connected at one end 21 to the center of one of the plates, as 17. The 70 plate 16 is rotatably mounted on the opposite end of the pintle 21 and retained in place thereon by a flat exterior head 22. The plates 16 and 17 with their flanges form a thin chamber 23 within which is placed a 75 flat spiral spring 24, the inner end of which is inserted in a perforation in the pintle 20, the outer end being attached to a pin 25, projecting from the casing plate 16 rotatable about said pintle.

Projecting radially from diametrically opposite sides of flange 18 of casing 15 are lugs 26, integral with the flanges, and each having a perforation therethrough for the pivotal attachment of a link 27. The links 85 are shaped to lie close against the edge or flanges of casing 15, and to extend in opposite directions about one fourth way around the periphery thereof. Similar lugs 28 project from the casing flange 19 and to them 90 are pivoted links 29 of like shape to links 27 and similarly placed about the edge of the casing. When the buckle is not under tension, the lugs 26 and 28 at opposite sides of the casing are held in mutual contact by 95 the spring 24 while the link 27, 29 of each pair of links pivoted to said lugs have their opposite ends in close relation and are pivoted to a loop 30 or other form of connecting means on the end of a belt or 100 strap 31.

The links 27, 29 may be made in various ways, the preferred form being that shown in Figs. 1, 2, 8 and 9. This link has a knuckle 32 on one end for pivotal connection with a loop 30 and an eye 33 on its opposite end to connect with a lug 26 or 28. The link is curved, as shown, to fit closely the edge of the casing, but may be of other shape if necessary to lie close to a casing of 110

other than circular or elliptical outline. The eyes 33 enable the links to swing toward the flat sides of the casing and assume positions at various angles to the 5 plane of the casing, a convenience when the article on which the buckle is attached is placed about a circular body, as with a belt or garter.

In Figs. 5, 10 and 11, the link 34 is pressed 10 from sheet metal and is of channel shape in cross section, the two ends 35 being alike for pivotal connection with a lug and a loop. Figs. 6 and 7 show a link 36 similar in outline to that just described, but made 15 solid instead of being channeled.

The loop 30 in Figs. 1 and 5 is elongated with an elongated opening 37 therein for the attachment of a strap and on one edge of said loop at the center are two projecting 20 lugs 38 for connection to links 27, 29. One or both loops 30 on each buckle may if desired be circular or of other shape, or one of them may be substituted for a hook of any well known shape, or for a small plate 25 40 on which is pivoted a slide, 41 through which passes a cord 42, such as is commonly used on suspenders.

In use, the normal position of the buckle is shown in Fig. 1, but when the belt or strap 30 31 is subjected to excess strain or pressure, the links 27, 29 pull the lugs 26, 28 laterally away from each other and cause the two

parts of the casing 15 to turn in opposite directions about their common axis, the spring 24 being tightened by this movement. 35 The parts will finally be drawn into the position illustrated in Fig. 5. When relieved of strain, the spring 24 returns the parts to normal position.

I claim:

In a device of the character described, a pair of circular plates pivotally connected together, each having a flanged marginal edge, said flanges contacting and forming an inclosed chamber, a pintle fixed to one 40 of said plates and rotatable relatively to the other plate, a spiral spring in said chamber surrounding said pintle and connected at one end to the same, the other end being connected to the relatively rotatable plate, a pair of lugs, diametrically disposed on the exterior of each of said plates, opposite members for attachment of tensioning devices, a link pivoted to each lug on one of said plates and to each tension member, and like links 45 pivoted to the lugs on the other plate and to the same tension members, for rotating said plates in opposite directions and tightening said spring, said links being curved 50 in the direction of their length to conform 55 to the circular contour of the plates.

In testimony whereof I affix my signature.

WALTER W. LAFLAME.
